CONTROL DEVICE FOR LIQUID FUEL
BURNERS

Rallston M. Sherman, Glastonbury, and Frederick F. Neumann, West Hartford, Conn., assignors to The Silent Glow Oil Burner Corporation, Hartford, Conn., a corporation of Connecticut

Application March 30, 1931, Serial No. 526,532

11 Claims. (Cl. 158—11)

This invention relates to liquid fuel burners and consists in improvements designed to increase their field of utility by the provision of suitable control devices such that the same burner may be employed with either liquid or gaseous fuel, or both. While other types of liquid fuel may be employed, for descriptive purposes the liquid fuel is herein referred to as oil.

The invention will be best understood by reference to the following description when taken in connection with the accompanying illustration, while its scope will be more particularly pointed out in the appended claims.

In the drawings:

15 Fig. 1 is a plan view of a control device comprising a control valve for the oil and a control valve for the gaseous fuel;

20 Fig. 2 is a central, sectional elevation of the control device shown in Fig. 1;

25 Figs. 3, 4, 5 and 6 are diagrams illustrating the relationship between the two valves at different stages in the operation of each;

Fig. 7 shows one method of connecting the control device of Fig. 1 to a liquid fuel burner of the 25 combustion tube type; and

Fig. 8 shows another method of connecting the device to the same type of burner.

Referring to the drawings and to the illustrative embodiment of the invention, there is shown 30 in Figs. 1 and 2 a control device adapted to be applied to an oil burner (as shown in Fig. 7) so constructed that it may be operated for either long or short intervals from a supply of either oil or gas, the controlling device being such that 35 the burner may be operated exclusively from a source of oil supply or from a source of gas supply, or its operation at one time when supplied with gaseous fuel may be followed without interruption by its operation with oil, or vice versa.

40 Referring to Fig. 2, the control device comprises two coordinated valves, a gas valve 11 of the rotary tapered type and an oil valve 13 of the needle type. The gas valve 11 comprises a tapered valve body fitting a tapered seat in the valve casing 15 45 in which the valve turns, the casing having at its lower end a gas supply passage 17. The passage 17 communicates freely with a cored passage extending part way into the lower end of the valve body and having a port 19 opening through 50 the side of the valve which, when the valve is suitably turned, registers with a delivery port 21 (see Figs. 3 to 5) which is in the side of the valve casing and communicates with the burner gas-supply pipe 22 (Figs. 1, 7 and 8).

55 The valve 11 is kept pressed tightly to its seat

by means of a spring 23 positioned in a recess in the valve casing encircling the valve stem 24 and confined between a washer on the valve stem and a threaded thimble 25 screwed into the top of the valve casing.

The oil valve 13 is provided with the valve stem 27 having threaded engagement with the valve casing 29, the stem having a shouldered lower end adapted, as the stem is screwed in or out of the casing, to be brought into engagement with the valve seat and over the oil supply port 31 to close the same, or to be retracted therefrom and to provide a very gradually enlarging port opening as the tapered end of the valve emerges more or less from the port. The supply port 31 opens 60 into the oil supply passage 33 at the lower end of the casing 29 and the valve when opened admits oil from the port 31 through a lateral passage in the side of the casing above the port to the burner oil-supply pipe 35.

The lower end of each valve casing is threaded 65 into the connecting yoke piece 41 which unites the two casings into a single structure and provides a coupling to which there may be screwed by threaded engagement the supply pipes 43 and 45 connected (Figs. 7 and 8), one to a source of gaseous fuel supply, and the other to a source of oil supply and adapted to supply gas and oil respectively to the gas and oil valves 17 and 33.

To turn the oil valve, the latter is provided 70 immediately above the casing with a gear 47 adapted to mesh with a segmental gear 49 secured to the gas valve stem when the latter is turned into a suitable angular relationship to the gear 47. The gears are covered by a plate 51 75 which fits over the valve stems and is held in position by the springs 53 and 55, respectively, encircling the protruding ends of the stems. The spring 53 is held in position by a nut 57 on the end of the oil valve stem 27 and the spring 55 is 80 held in position by a handle 59 fastened to the top of the gas valve stem 54.

The handle 59 has a projecting finger 61 which, by engagement with the end of an arc-shaped, raised, stop lug 63, limits the movement of the 85 valve stem in either direction. The diametrically opposite finger 65 of the handle is inclined upwards so that in the rotative movement of the stem it clears the stop lug 63.

The valve ports with their connected gears are 90 represented in Figs. 1, 2 and 3 in the closed position of each. If it is desired to open the gas valve to start the burner with gas, the handle 59 is turned counterclockwise to supply gas to the burner and may be turned to the full open posi- 95 100 105 110

tion represented in Fig. 4 or any intermediate position, dependent on the supply of gas desired. The valve may be left in that position for any desired length of time and the burner operated 5 as a gas burner.

If it is desired to employ oil as a fuel and to utilize the gas flame merely for preheating the burner, after the burner has acquired a temperature such that the oil may be turned on with the 10 assurance of its being vaporized as soon as it enters the burner, the valve is then turned to some such position as is represented in Fig. 5, diminishing somewhat the supply of gas and causing the 15 segmental gear 49 to engage the oil valve gear 47 and turn the latter slightly to partly open the oil 20 port and admit a limited supply of oil. As soon as the combustion of the oil is completely established the valve is then turned to some such position as is shown in Fig. 6, where the gas supply 25 is completely cut off and the burner works exclusively under the supply of oil, the handle being capable of being turned still further to increase the supply of oil as may be required.

Preferably the pitch of the threads on the oil 25 valve stem 27 is such as to give a port opening under the partial rotation of the gear 47 here provided for, sufficient to yield the maximum supply of oil which is required.

One or both of the gears 47 and 49 are preferably 30 so mounted on their respective valve stems as to be capable of some angular adjustment. In the illustrated form of the invention, the valve stems are provided with teeth or notches over which the 35 gears fit with interengaging recesses, so that when desired either one may be slipped off and again applied in either slightly advanced or backward position with relation to the stem.

In Fig. 7 we have shown the connection and 40 relationship of the control device to a typical oil burner of the combustion tube type. The latter is provided with the base member 67 having an inner, annular, broad oil vaporizing groove 69 and an outer, annular, concentric groove 71, the two 45 grooves being connected by fuel supply conduits (not herein shown). Annular air admission openings 73 are provided between the two grooves and a central air passage 75 within the inner groove 69. The outer groove 71 is formed between upright flanges which support perforated combustion 50 tubes 77 and 79, forming between them a combustion chamber open at the top. A similar inner combustion chamber, also open at the top and separated from the first combustion chamber by an intervening annular air space, is formed between the perforated combustion tubes 81 and 83, seated one on the outer flanged wall of the groove 69 and the other on the outer edge of the removable cover plate 85 which partially covers a portion of the broad fuel groove but leaves the outer 55 portion thereof aligned with and communicating with the overhead combustion chamber. The top of the central air chamber and the intermediate annular air chamber being closed, fuel admitted 60 to and ignited in or immediately above the fuel 65 grooves commingles with the air supplied through the perforated walls of the combustion tubes and burns therein, with a blue flame issuing from the open tops of the two concentric combustion chambers.

70 While the fuel grooves may be in free and open communication with the overlying combustion chambers, herein the bottom of each combustion chamber is separated from the underlying fuel groove by a partition formed by a plate 87, each 75 plate being provided with a series of restricted

orifices or their equivalent, so that, while permitting the passage from the fuel groove to the overhead combustion chamber of either gaseous fuel or vaporized oil, the burning thereof is confined to the combustion space and the flow of gaseous vapor is sufficiently restricted to cause a substantially even distribution thereof as it circulates throughout the fuel spaces and a substantially uniform combustion throughout both combustion chambers whether supplied with gas or 80 with oil.

In Fig. 7 the burner gas-supply pipe 22 is connected to the burner to deliver gas into the outer fuel groove 71, while the burner oil-supply pipe 35 is connected to supply oil through an 90 opening in the base plate 67, delivering it directly to the bottom of the broad vaporizing groove 69.

In the arrangement shown in Fig. 8, a burner 95 similar to that illustrated in connection with Fig. 7 is shown, but both the burner gas-supply pipe 22 and the burner oil-supply pipe 35 are connected to deliver each its supply through a common delivery pipe 89 which discharges 100 through an opening also in the bottom of the 100 broad fuel passage 69.

It will be observed that the two valves are so related that in cutting off the gas from the burner and opening the oil supply thereto, as in passing from the position shown in Fig. 4 to that shown 105 in Fig. 6, or in cutting off the oil and opening the gas supply, as in passing from the position shown in Fig. 6 to that shown in Fig. 4, an intermediate position, such as shown in Fig. 5, is passed through in which both gas and oil are temporarily 110 supplied. This insures the persistence of the combustion in the burner during the time that change is being made from one type of fuel to the other so that the operation of the burner may proceed without interruption. It further facilitates the action of starting the burner with oil 115 after preheating with gas, since the continuing pressure in the gas supply, as the oil is turned on, checks the too sudden delivery of oil to the vaporizing space, allowing it to flow more gradually over the bottom plate thereof and insuring its instant vaporization by the preheated walls.

When the burner is in operation the base and the vertical supply pipe connected to the base 120 become highly heated and, when supplied with oil, partial vaporization, at least, of the oil begins to take place in the pipe at a substantial distance below the base. In the form shown in Fig. 8, the burner may be started with gas which is supplied under any suitable or desired pressure. 125 When the valve is moved to admit the first small initial supply of oil, a minute but gradually increasing amount of the latter enters the horizontal pipe 89, where it passes over with the gas into the vaporizing zone in the vertical pipe, supplying vaporized oil to the burner to off-set the diminishing supply of gas. The gas, however, is left free to force its way through the vertical supply pipe to the burner under the supplied 130 pressure until, as the gas supply decreases and the fuel supply becomes mainly or wholly vaporized oil, the vaporization of the latter is sufficient to maintain the burner in full fire operation.

The ordinary combustion tube burner, when supplied solely with liquid fuel, has certain disadvantages which limit its field of usefulness. In starting a burner of this type from a cold condition it is necessary to preheat the burner walls 145 before finally turning on the full continuing supply of the liquid fuel so that some vaporization 150

of the fuel will take place when it reaches the fuel space and the rising vapor ignites with the incoming air in the combustion chamber.

The prolonged interval required for the pre-

5 heating before the burner can be brought to its full heating capacity, which may be termed the starting interval, is a serious drawback to the more general use of this type of burner. Due also to the fact that the oil or other fuel is de-
10 livered in liquid form and must be vaporized by the heated surrounding walls of the burner before it can be ignited in the combustion chamber, the heating effect of an oil burner of given size is limited and, while it may be ample for or-
15 dinary purposes, if an especial occasion arises calling for a more intense heat, the burner cannot be forced beyond a given point by merely increasing the rate with which liquid fuel is supplied.

In the described embodiment of the invention, 20 if it is desired to operate the burner with liquid fuel, the starting interval may be cut down to a relatively short period by first turning on and igniting the gas from the source of gas supply which will immediately develop the full heating 25 capacity of the burner and will quickly raise the temperature of the burner walls to a point sufficient to fully vaporize the oil. Accordingly the latter, without the long delay heretofore necessary, may be quickly turned on and the gas shut off, almost immediately reaching the full oil-
30 heating capacity of the burner under the supply of liquid fuel, thereby eliminating in large measure the disadvantage due to a prolonged starting interval.

35 On the other hand, where it is desired usually to operate the burner under liquid fuel but at times to operate it under conditions of more intense heat than could be obtained by liquid fuel, the latter may be shut off and the gas turned on 40 to force the burner beyond its liquid-fuel heating capacity and to give whatever degree of flame may be called for.

The construction of the burner which qualifies 45 it to burn either type of fuel adapts it to a wide range of conditions. If gas is readily available and relatively economical it may be employed primarily with gas, and liquid fuel may be drawn from a source of liquid fuel supply only on those occasions when, as often happens, the gas supply 50 may fail or be inadequate. If, as is usually the case, liquid fuel is more economical than gas, the burner may be primarily operated from the source of liquid fuel and operated with gas only for preheating or when the liquid fuel supply is 55 depleted or not available, or when a special occasion arises for forcing the burner beyond a heating capacity which is obtainable from the liquid fuel. On the other hand, the burner may be operated at will exclusively by liquid fuel or ex-
60clusively with gas, as circumstances may demand.

The source of oil supply may comprise an elevated tank or the like combined with any feeding devices customarily employed with burners of this type and which provide for the flow of oil to the burner from some definite height or level capable of being accurately regulated, so that the flow of fuel may be maintained at a predetermined level over the flow plate or bottom of the broad vaporized groove 69 in the burner. Such 65 tanks and regulating devices are of common construction and are not herein shown. The source of gaseous fuel supply may be the ordinary service main or a gas-containing storage tank where the gas is maintained under pressure, or any other 70 suitable source.

If, during the operation of the burner under oil, it is desired to force the burner beyond its oil heating capacity, the valve may be turned back from the oil supplying position, shown in Fig. 6, to the gas supplying position, and when turned 80 to its full gas supplying position, shown in Fig. 4, it will produce a flame of greater volume and heating intensity than can be had from the oil supply. Similarly should any occasion arise for switching from one type of fuel to the other, either 85 because of the depletion or failure of the oil supply or the temporary or other failure of the necessary pressure in the gas main or other source, or for any other reason, such switch or change may be immediately made without alteration in 90 the burner itself.

While we have herein described for purposes of illustration one specific embodiment of the invention and one particular application thereof, it is to be understood that extensive deviations 95 from and changes in the illustrated form may be made and applications thereof other than herein illustrated may be utilized, all without departing from the spirit of the invention.

We claim:

1. The combination with a burner having a combustion chamber, of a source of liquid fuel supply connected thereto, a source of gaseous fuel supply communicating with said combustion chamber, separate valves for controlling the supply of fuel to the burner from said sources, means for operating one of said valves, and means for coordinately operating the other valve comprising a segmental gear connected to one valve and an intermeshing gear connected to the other constructed for effecting movement of one valve without movement of the other.

2. The combination with a burner having a combustion chamber, of a source of liquid fuel supply connected thereto, a source of gaseous fuel supply communicating with said combustion chamber, separate valves for controlling the supply of fuel to the burner from said sources comprising a rotary gas valve and a positively seating oil valve, and means interconnecting said valves to move the same coordinately together or to move said gas valve alone when the oil valve is seated.

3. The combination with a burner having a combustion chamber, of a source of liquid fuel supply connected thereto, a source of gaseous fuel supply communicating with said combustion chamber, means for controlling the supply of fuel from said sources comprising a rotary gas valve member and a rotary positively seating liquid fuel valve member, and means interconnecting said valves to move said valve members coordinately or to provide for the movement of the said gas valve member to full open position while the liquid fuel valve member is still closed.

4. The combination with a burner having a combustion chamber, of a source of liquid fuel supply connected thereto, a source of gaseous fuel supply communicating with the combustion chamber, a valve for controlling the gas supply, a separate valve for controlling the liquid fuel supply, and means for actuating the valves including gearing connections between the valves constructed for movement of the gas valve to its full open position to supply gas to the combustion chamber of the burner while maintaining the liquid fuel valve closed, for opening movement of the liquid fuel valve with shutting off of the gas to supply liquid fuel to the fuel receiving space of the burner, and, in the change from gas supply to liquid

fuel supply, for continuance of the gas supply until the liquid fuel supply has been established.

5. The combination with a burner having a combustion chamber, of a source of liquid fuel supply connected thereto, a source of gaseous fuel supply communicating with said combustion chamber, a valve for controlling the gas supply, a separate valve for controlling the liquid fuel supply, and interconnections between said valves constructed for movement of each to a full open position to connect the burner exclusively with either source of supply, said connections constructed for effecting a closing movement of one valve on the opening movement of the other.

15. 6. The combination with a burner having a combustion chamber, of a source of liquid fuel supply connected thereto, a source of gaseous fuel supply communicating with the combustion chamber, a valve for controlling the gas supply, a separate valve for controlling the liquid fuel supply, connections between said valves constructed for effecting the continuance of the established supply from one source until the supply from the other source has been established, said connections permitting movement of said valves each to its full open position to connect the burner exclusively with either source of supply.

7. The combination with a burner having a combustion chamber, of a source of liquid fuel supply connected thereto, a source of gaseous fuel supply communicating with the combustion chamber, a valve for controlling the gas supply, a separate valve for controlling the liquid fuel supply, means for actuating the valves including connections between the valves constructed for movement of the gas valve to its full open position to supply gas to the combustion chamber of the burner while maintaining the liquid fuel valve closed, said connections further constructed for effecting opening movement of the liquid fuel valve to supply liquid fuel to the fuel receiving space of the burner with simultaneous shutting off of an established supply of gaseous fuel, and in the change from gas supply to liquid fuel supply, constructed for effecting a continuance of established gas supply until the liquid fuel supply has been established.

8. The combination with a burner having a combustion chamber, of a source of liquid fuel supply connected thereto, a source of gaseous fuel supply for the combustion chamber, separate valves for controlling said supplies, and inter-

connections between the valves constructed for effecting the closing movement of one valve through the opening movement of the other, said connections including a lost motion provision constructed so that the gas valve may be moved to its full open position while maintaining the liquid fuel valve closed.

9. The combination with a burner having a combustion chamber, of a source of liquid fuel supply connected thereto, a source of gaseous fuel supply for the combustion chamber, separate valves for controlling said supplies, and interconnections between the valves constructed for effecting the closing movement of one valve through the opening movement of the other, said connections including a lost motion provision constructed so that one valve may be moved to its full open position while maintaining the other valve closed.

10. The combination with a burner having a combustion chamber, of a source of liquid fuel supply connected thereto, a source of gaseous fuel supply communicating with the combustion chamber, a valve for controlling the gaseous fuel supply, a separate valve for controlling the liquid fuel supply, means for operating said gaseous fuel supply valve to move it to its full open position while maintaining the liquid fuel supply valve closed, means for moving the liquid fuel supply valve to its full open position while maintaining the gaseous fuel supply valve closed, and interconnections between the valves constructed to utilize the opening movement of one valve to cause the closing movement of the other valve.

11. The combination with a burner of the combustion tube type having spaced perforated walls providing between them an elongated combustion chamber, of a base member presenting a fuel receiving space opening into the combustion chamber, a source of liquid fuel supply, a source of gaseous fuel supply, a valve for controlling the gaseous fuel supply, a separate valve for controlling the liquid fuel supply, a common supply pipe connecting both valves with the fuel receiving space of the burner, and means for actuating the valves to connect the burner exclusively with either source of supply, including connections between the valves constructed for effecting closing movement of one valve on opening movement of the other.

RALLSTON M. SHERMAN.
